UNITED STATES PATENT OFFICE.

VERNON BALFOUR HARLEY-MASON, OF CHEAM, AND REGINALD JOHN FISHER, OF EPSOM, ENGLAND.

STEAM-EXPANSION ENGINE.

Application filed March 20, 1924, Serial No. 709,648, and in Great Britain March 26, 1923.

This invention relates to steam or the like expansion engines and has reference particularly to steam engines where steam is expanded between a hollow piston and a cylinder cover conforming to the internal contour of the piston.

The invention is particularly advantageous in an engine as disclosed in the specification of Letters Patent Nos. 1,145,391 and 1,230,617 granted to William Joseph Still which, although an internal combustion engine, also operates under steam expanded at the back of the combustion piston.

In such engines some of the steam is expanded under the edge of the piston skirt between it and the base of the conforming cover, but the major portion is expanded behind the piston crown, between it and the extremity of the conforming cover. For the purposes of this specification this latter space will be referred to as the steam cylinder.

In engines of this type it is necessary to provide a passage between the valve or valves and the steam cylinder for the admission and exhaust of the steam to and from the cylinder, and it is found in practice that the cross sectional area of passage necessary for admitting steam to the cylinder is considerably smaller than that necessary for adequately exhausting it. This passage must therefore, be large enough for the latter purpose. In cases where it is necessary or desirable to place the valves outside the conforming cover, this passage must traverse the whole length of the piston skirt and as its whole volume acts as clearance volume, this clearance volume becomes normally large.

The object of the invention is to assure that the clearance volume due to this passage is reduced to the equivalent of a similar passage of sufficient area for admitting steam.

With this object in view the invention consists broadly of a steam expansion engine, in which steam is expanded on the underside of the piston, comprising a cylinder cover which conforms both to the interior of the piston and to the exterior of the piston rod, which rod is so spaced from the surrounding part of the cover as to provide a passage for the steam and is so shaped that the cross sectional area of the passage increases during the stroke so as to

provide, towards the end of the stroke a cross sectional area sufficient to adequately exhaust the steam.

The invention may conveniently be carried into effect by making the piston rod and the conforming part of the cylinder cover of conical or stepped form and providing between them an annular passage for the steam.

In order that the invention may be clearly understood two embodiments of the same will now be described by way of example, by aid of the accompanying somewhat diagrammatic drawings in which:—

Figure 1 is a longitudinal section through a conforming piston and cylinder cover according to one embodiment of the invention showing the piston at the commencement of its stroke.

Figure 2 is a similar view but showing the position of the piston relative to the conforming cover when the piston has completed its outward stroke.

Figure 3 is a similar view showing the position of the piston when it has completed half its return stroke.

Figures 4 and 5 correspond in all respects to Figures 1 and 2 respectively excepting that the same illustrate the second embodiment of the invention wherein the piston rod is of conical form.

Corresponding parts will be referred to throughout the specification by like reference numerals.

In the drawings 10 represents the cylinder cover which projects up into the interior of the cylinder, not shown, and which also embodies the steam inlet and exhaust ports 11 and 12 respectively.

This cover is annular in form and comprises inner and outer walls 13 and 14 respectively, the outer wall 14 conforming to the interior of the piston 15 and the inner wall 13 conforming to the piston rod 17. The rod 17 and inner wall 13 are in the axamples illustrated in Figures 1, 2 and 3 of stepped form, and of such relative diameter as to provide an annular passage 18 between them, such passage functioning as an inlet passage for the steam on the outward stroke of the piston and an exhaust passage for the steam on the return stroke of the piston.

By reason of the stepped or conical form of the conforming parts of the piston rod and cover the cross sectional area of the pas-

sage 18 at the commencement of the stroke of the piston is sufficient for the proper admission of the steam required, such cross sectional area increases however as the piston moves away from the cover so that when the piston commences its return or exhaust stroke the cross sectional area of this passage is at a maximum and, in the examples illustrated in Figures 1 and 3, such maximum area is maintained through a distance indicated in the drawings, that is until the piston reaches the position shown in Figure 3 after which the cross sectional area is reduced until the minimum is again reached when or before the piston reaches the end of its return stroke. Such reduction in cross sectional area is however no detriment in practice as by the time the piston has reached the position shown in Figure 3 most of the steam has passed out of the exhaust port. Further it is frequently desirable that a certain proportion of the steam be trapped in the cylinder to provide the desired cushioning effect of the end of the stroke and for this reason the exhaust valve will be shut or shutting when the piston is in the position indicated in Figure 3.

With the embodiment illustrated in Figures 4 and 5 the reduction in cross sectional area of the passage 18 is more gradual than is the case with the embodiment illustrated in Figures 1 and 3 as also is the increase in cross sectional area at the commencement of the stroke.

It will thus be seen that by means of this invention the clearance volume of the pas-

sage 18 is reduced to the equivalent of a passage of sufficient area for admitting steam.

Further the invention is particularly applicable in engines where further reduction of inlet area is possible due to short cut off and hence low piston speed during admission.

What we claim and desire to secure by Letters Patent is:—

1. A steam expansion engine comprising a cylinder, a piston within said cylinder, a piston rod of diminishing diameter from its inner end to its outer end, a cylinder cover conforming to both the interior of the piston and the exterior of the piston rod and a space between the interior of said cover and the exterior of said piston rod constituting a passage for admitting steam to the underside of the piston which passage increases in cross sectional area during the stroke. 50 55

2. A steam expansion engine comprising a cylinder, a piston within said cylinder, a piston rod of stepped form the largest diameter being at the end adjacent to the piston, a cylinder cover conforming to both the interior of the piston and the exterior of the piston rod and a space between the interior of said cover and the exterior of said piston rod constituting a passage for admitting steam to the underside of the piston which passage increases in cross sectional area during the stroke. 60 65

In witness whereof we affix our signatures.
